TURNING DEVICE

Edwin J. Kratzenberg, Chicago, Ill., assignor to
United States Steel Company, a corporation of
New Jersey

Application December 10, 1949, Serial No. 132,308

12 Claims. (Cl. 198—33)

1

This invention relates to turning devices particularly for turning articles axially, such as steel billets between successive roll passes.

In rolling billets, for example, the usual practice is to turn each billet axially 90° after each pass through the rolls. As billets leave a heating furnace, their lower faces are cooler than their upper faces and they must not be rolled with their cool faces up or their ends will bow upwardly so that they cannot enter the next pass. Therefore, in successive passes billets are oriented with the cool face directed alternately toward one side and downwardly. Billets can have only a closely restricted lateral motion between passes, or else they would not be in position to enter the succeeding pass.

An object of the present invention is to provide improved turning devices which mechanically turn articles axially while changing their lateral position only within a closely restricted distance.

A further object of the invention is to provide improved devices for turning articles which are traveling along a supporting and conveying structure, such as a roller table, and keeping the major portion of the weight of the article on the supporting and conveying structure during the turning operation.

A further object of the invention is to provide improved turning devices which include a tumbler adapted to roll laterally and having an open sector for receiving and turning articles, such rolling compensating for shifting of the article, whereby the article remains within a closely restricted lateral space.

A further object of the invention is to provide improved turning devices which mechanically turn articles such as billets axially and keep successive articles in the same orientation.

In accomplishing these and other objects of the invention, I have provided improved details of structure, a preferred form of which is shown in the accompanying drawings, in which:

Figure 1 is a top plan view of an improved turning device which embodies features of the present invention;

Figure 2 is a vertical sectional view taken substantially on line II—II of Figure 1;

Figure 3 is a view similar to Figure 2, but showing the parts in a different position; and

Figure 4 is a vertical sectional view taken substantially on line IV—IV of Figure 1.

Figure 1 illustrates the turning device of the present invention in conjunction with a roller table, which includes the usual beams 10, rollers 12 and side guards 13. These rollers and guards

2

direct articles, such as billets B, between successive roll passes, not shown, but which can be of any standard construction.

The turning device of the present invention comprises a main frame which is fixed across the roller table beams 10 between a pair of rollers 12, guards 13 being interrupted in this space. Said frame includes spaced parallel transverse beams 14 and braces 15 bolted or otherwise secured together to form a rigid structure. The inner faces of beams 14 carry fixed track members 16. The upper faces of said beams carry a stand 17, the position of which can be adjusted along the length of the beams. Conveniently dowel pins 18 retain the stand in its adjusted position on the beams, the upper flanges of the beams having a series of apertures 19 for receiving said dowel pins. The stand has upright pins 20 on the left and 20a on the right which carry means, such as tapered rollers 21 and 21a, respectively for guiding articles as they turn within the device as hereinafter explained. Preferably brace structures 22 and 22a extend across the stand and are connected to the upright pins 20 to stiffen them. These braces can have handles to facilitate removing or adjusting the stand for moving the roll pass sideways.

Track members 16 support a carriage which includes a rigid chassis 23 and rollers 24 and 24a. Said rollers ride on said track members so that the carriage can move along the main frame transverse to the movement of articles on the roller table. The main frame includes a horizontal platform 25 which supports motive means for the carriage. This motive means includes a fluid pressure cylinder 26 and a double-acting piston 27 mounted for reciprocable movement in said cylinder. A piston rod 28 and a connecting bar 29 connect said piston and carriage chassis 23. Therefore reciprocation of the piston within the cylinder moves the carriage along the trackway.

The carriage supports a tumbler 30 within the confines of stand 17. The carriage chassis 23 has inwardly extending flanges 31 (Figure 4) and the outer surface of the tumbler has a cylindrical portion 32 which rests on said flanges. A first pair of flexible elements 33 (Figures 2 and 3) is connected to the upper edge of cylindrical surface portion 32 at 34, extends around this surface, and is connected to the carriage chassis at 35. A second pair of flexible elements 36 is connected to the lower edge of cylindrical surface portion 32 at 37, extends around this surface, and is connected to the carriage chassis

at 38. The tumbler includes an off center pin 39 which has protruding end portions that ride above the carriage top. Stand 17 has abutments 40 on the left and 40a on the right with which said pin is engageable for limiting lateral movement of the tumbler. The tumbler has an open sector 41 which faces upwardly and toward one side and is adapted to receive articles.

Figure 2 shows the position of the parts when piston 27 is in its fully extended position. The open sector 41 of tumbler 30 occupies the upper right quadrant of the tumbler. One radial face 42 of this sector is horizontal and is situated approximately a half inch below the upper surface of table rollers 12. The other radial face 43 of this sector is upright and is spaced somewhat outwardly of the inner faces of tapered rollers 21 on the left. In this position the open sector of the tumbler can receive an article, such as billet B, which is moving along the roller table. Figure 3 shows the position of the parts when piston 27 is in its fully retracted position. The open sector of the tumbler now occupies the upper left quadrant of the tumbler and radial face 43 is horizontal and is situated about a half inch below the tops of rollers 12. The open sector thus is positioned to discharge the article to the roller table with the article turned axially 90°.

When the piston moves between the positions shown in Figures 2 and 3, the carriage moves along track members 16. Flexible elements 36 in effect gear the tumbler to the carriage chassis so that movement of the carriage moves the tumbler and article laterally until the article contacts rollers 21a on the right. Further movement of the carriage rolls the tumbler counter-clockwise along flanges 31 of the carriage chassis 23. As the tumbler rolls, flexible elements 36 unwind from cylindrical surface portion 32 while the other flexible elements 33 wind on this surface portion. Other connecting means, such as a rack on the carriage and gear teeth on the tumbler, would be mechanically equivalent to the flexible elements. The tumbler continues to roll until the article and the tumbler turn counter-clockwise 90°. Thereupon the tumbler (but not the article) resumes its lateral movement along with the carriage. The carriage and tumbler continue to move laterally until piston 27 completes its stroke, which can be anywhere in advance of the point of engagement of pin 39 with abutments 40a on the right.

As the article is turning, it pivots about its lower left edge as viewed in Figure 2, or its lower right edge as viewed in Figure 3. The major portion of the weight of the article remains on the roller table. Therefore a relatively light weight carriage and tumbler can turn a heavy article, such as, for example, a one ton billet. The initial lateral movement of the tumbler carries the article laterally to the right side of the pass and the subsequent rolling of the tumbler and pivoting of the article about its lower edge returns it to the left side of the pass. Pin 39 is located off-center to remove it from the open sector of the tumbler where the article rests.

After the article leaves the tumbler, and the piston completes its stroke, the carriage can turn to the position shown in Figure 2. As the carriage returns, the tumbler tends merely to move laterally with the carriage without turning until pin 39 contacts abutments 40 on the left. On continued movement of the carriage beyond this position, flexible elements 33 unwind from the cylindrical surface portion and turn the tumbler

clockwise. The other flexible elements 36 wind on the cylindrical surface portion. Thus the tumbler reaches a position in which it is ready to receive another article. The turning device can be double-acting; that is, it can turn another article axially on its return stroke. However, for turning billets I prefer that it be single-acting in order that the billets always turn in the same direction so that the same orientation is preserved on succeeding billets.

Conveniently photo-electric means 44 can be employed for controlling operation of piston 27. Said photo-electric means can be focused ahead of the turning device so that as the article reaches the proper position with respect to the turning device it actuates the photo-electric means. The latter then actuates piston 27 through any convenient circuit. After the article leaves the turning device, the photo-electric means can return the turning device to its original position.

Preferably connecting bar 29 is replaceable with bars of different lengths. When stand 17 is adjusted to a different position on the main frame, bar 29 can be replaced to effect a corresponding adjustment in the right and left positions of the carriage and tumbler without changing the position of cylinder 26. Otherwise this cylinder can be adjustably mounted on supporting platform 25. Also the tapered rollers 21 and 21a can be made laterally adjustable to narrow or widen the pass for smaller or larger articles.

From the foregoing description it is seen that the present invention provides a simple and practical mechanical device for turning articles axially, for example, steel billets between roll passes. The device maintains such articles within a restricted lateral space as they turn, and successive articles in the same orientation. The supporting and conveying structure, such as the roller table illustrated, carries the major portion of the weight of the article at all times.

While I have shown and described only a single embodiment of the invention, it is apparent that modifications may arise. For example, by proper positioning of the stop means and adjusting of the piston stroke, the tumbler can turn through angles other than 90°. Therefore, I do not wish to be limited to the disclosure set forth but only the scope of the appended claims.

I claim:

1. A turning device comprising a frame, a carriage movably supported on said frame, article receiving means supported on said carriage for rolling movement with respect thereto, stop means fixed with respect to said frame for limiting movement of said article receiving means, and connecting means between said article receiving means and said carriage for rolling said article receiving means when said carriage moves beyond the position at which said stop means limits movement of said article receiving means.

2. A turning device comprising a main frame, a carriage movably supported on said main frame, article receiving means supported on said carriage for rolling movement with respect thereto, stop means fixed with respect to said frame for limiting movement of said article receiving means, flexible elements connecting said article receiving means and said carriage for rolling said article receiving means when said carriage moves beyond the position at which said stop means limits movement of said article receiving means, and motive means for moving said carriage.

3. A turning device comprising a main frame,

a carriage, means movably supporting said carriage on said main frame, article guiding means on said main frame, a tumbler supported for lateral rolling movement along said carriage and having an open sector adapted to receive articles, stop means fixed with respect to said main frame and with which said tumbler is engageable for limiting the lateral positions of said tumbler, and means connecting said carriage and said tumbler and rolling tumbler and thereby turning an article carried therein when said carriage moves either beyond a position in which the articles engage said guiding means or beyond a position in which said tumbler engages said stop means.

4. A turning device comprising a main frame, a carriage, track means movably supporting said carriage on said main frame, article guiding means on said main frame, a tumbler supported for lateral rolling movement along said carriage and having an open sector adapted to receive articles, abutments fixed with respect to said main frame and with which said tumbler is engageable for limiting the lateral positions of said tumbler, flexible elements connecting said carriage and said tumbler and rolling said tumbler and thereby turning an article carried therein when said carriage moves either beyond a position in which the article engages said guiding means or beyond a position in which said tumbler engages said abutments, and motive means for moving said carriage.

5. A turning device comprising a main frame, a carriage, track means movably supporting said carriage on said main frame, upstanding article guiding means on said main frame, a tumbler having a cylindrical outer surface portion supported for lateral rolling movement along said carriage and having an open sector adapted to receive articles, abutments fixed with respect to said main frame and with which said tumbler is engageable for limiting the lateral positions of said tumbler, and means connecting said carriage and said tumbler and rolling said tumbler and thereby turning an article carried therein when said carriage moves either beyond a position in which the article engages said guiding means or beyond a position in which said tumbler engages said abutments.

6. A turning device comprising a main frame, a carriage, track means movably supporting said carriage on said main frame, upstanding article guiding means on said main frame, a tumbler having a cylindrical outer surface portion supported for lateral rolling movement along said carriage and having an open sector adapted to receive articles, abutments fixed with respect to said main frame and with which said tumbler is engageable for limiting the lateral positions of said tumbler, first flexible elements connected to one edge of the cylindrical surface portion of said tumbler, extending around this portion and being connected to said carriage, and second flexible elements connected to the other edge of the cylindrical surface portion, extending around this portion and being connected to said carriage, said flexible elements rolling said tumbler and thereby turning an article carried therein when said carriage moves either beyond a position in which the article engages said guiding means or beyond a position in which said tumbler engages said abutments.

7. A turning device comprising a main frame, a stand adjustably carried on said main frame, article guiding means on said stand, track means fixed to said main frame, a carriage movably

supported on said track means, a tumbler supported for lateral rolling movement on said carriage within the confines of said stand and having an open sector adapted to receive articles, abutments on said stand with which said tumbler is engageable for limiting the lateral positions of said tumbler, and means connecting said carriage and said tumbler and rolling said tumbler when said carriage moves beyond positon in which said tumbler engages said abutments.

8. A turning device comprising a main frame, a stand adjustably carried on said main frame, track means fixed to said main frame, a carriage movably supported on said track means, a tumbler having a cylindrical outer surface portion supported for lateral rolling movement along said carriage within the confines of said stand and having an open sector adapted to receive articles, abutments on said stand with which said tumbler is engageable for limiting the lateral positions of said tumbler, first flexible elements connected to one edge of the cylindrical surface portion of said tumbler, extending around this portion and being connected to said carriage, second flexible elements connected to the other edge of the cylindrical surface portion, extending around this portion and being connected to said carriage, said flexible elements rolling said tumbler when said carriage moves beyond positions in which said tumbler engages said abutments, and motive means for moving said carriage.

9. A turning device comprising a main frame, a stand adjustably carried on said main frame, upstanding rollers on said stand for guiding articles, track means fixed to said main frame, a carriage movably supported on said track means, a tumbler having a cylindrical outer surface portion supported for lateral rolling movement along said carriage within the confines of said stand and having an open sector adapted to receive articles, abutments on said stand with which said tumbler is engageable for limiting the lateral positions of said tumbler, first flexible elements connected to one edge of the cylindrical surface portion of said tumbler, extending around this portion and being connected to said carriage, second flexible elements connected to the other edge of the cylindrical surface portion, extending around this portion and being connected to said carriage, said flexible elements rolling said tumbler and thereby turning an article carried therein when said carriage moves either beyond a position in which the article engages said upstanding rollers or beyond a position in which said tumbler engages said abutments, and motive means for moving said carriage.

10. In combination with an article supporting and conveying means, a turning device comprising a main frame transverse to said supporting and conveying means, a carriage, means supporting said carriage for movement on said main frame transversely of movement of articles on said supporting and conveying means, a tumbler supported on said carriage for rolling movement transversely of movement of articles on said supporting and conveying means and having an open sector for receiving articles from said supporting and conveying means, abutments fixed with respect to said main frame and with which said tumbler is engageable for limiting the transverse positions of said tumbler, means connecting said carriage and said tumbler and rolling said tumbler when said carriage moves beyond positions in which said tumbler engages said abutments, and motive means for said carriage.

11. In combination with an article supporting and conveying means, a turning device comprising a main frame transverse to said supporting and conveying means, a carriage, track means movably supporting said carriage on said main frame for movement transversely of movement of articles on said supporting and conveying means, a tumbler having a cylindrical outer surface portion supported on said carriage for rolling movement transversely of movement of articles on said supporting and conveying means, and having an open sector for receiving articles from said supporting and conveying means, abutments fixed with respect to said main frame and with which said tumbler is engageable for limiting the transverse positions of said tumbler, first flexible elements connected to one edge of the cylindrical surface portion of said tumbler, extending around this portion and being connected to said carriage, second flexible elements connected to the other edge of the cylindrical surface portion, extending around this portion and being connected to said carriage, said flexible elements rolling said tumbler when said carriage moves beyond a position in which said tumbler engages said stop means, and motive means for moving said carriage.

12. In combination with an article supporting and conveying means, a turning device comprising a main frame transverse to said supporting and conveying means, a stand adjustably carried on said main frame, article guiding means on said stand, track means fixed to said main

frame, a carriage supported on said track means for movement transversely of movement of articles on said supporting and conveying means, a tumbler supported on said carriage within the confines of said stand for rolling movement transversely of movement of articles on said supporting and conveying means and having an open sector adapted to receive articles, abutments on said stand with which said tumbler is engageable for limiting the transverse positions of said tumbler, means connecting said carriage and said tumbler and rolling said tumbler and thereby turning an article carried therein when said carriage moves either beyond a position in which the article engages said article guiding means or beyond a position in which said tumbler engages said abutments, and motive means for moving said carriage.
